UNITED STATES PATENT OFFICE.

FRANCIS BOYD, OF NEWBURG, NEW YORK.

DESIGN FOR BASIN-FRONT.

Specification forming part of Design No. 5,042, dated June 27, 1871.

To all whom it may concern:

Be it known that I, FRANCIS BOYD, of Newburg, in the county of Orange and State of New York, have invented and produced a new and original Design for Basin-Front; and I do hereby declare that the following is a full, clear, and exact description of the same, reference being had to the accompanying drawing forming a part of this specification.

My invention relates to a new design for a silt basin-front, to be applied to the corners of sidewalks at points where the gutters, &c., discharge into the sewers.

The nature of the design is shown in the ac-

companying drawing, in which A represents the vertical part of the basin-front, having suitable openings *a a* for the admission or passage of water, and B a horizontal flange which is intended to be flush with the adjacent portion of the bed or surface of the street-pavement.

I claim as my invention—

The design for a basin-front, substantially as shown.

FRANCIS BOYD.
